(57) **CLAIM**

The ornamental design for a light fixture including non-opaque light cover and light fixture body, as shown and described.

DESCRIPTION

FIG. 1 is a perspective of light fixture including a non-opaque light cover and a light fixture body;

FIG. 2 is a front elevational view of the light fixture, the back, left, and right elevational views being identical to the front elevational view;

FIG. 3 is a top plan view of the light fixture; and,

FIG. 4 is a bottom plan view of the light fixture, openings in a bottom of the light fixture body being shown in broken lines. The broken lines in the drawings indicate environmental structures which form no part of the claimed design.
